UNITED STATES PATENT OFFICE.

MILO A. ELLIOTT, OF WATERVILLE, MAINE.

MOP-WRINGER MACHINE.

No. 856,235.

Specification of Letters Patent.

Patented June 11, 1907.

Application filed February 23, 1906. Serial No. 302,550.

To all whom it may concern:

Be it known that I, MILO A. ELLIOTT, a citizen of the United States, residing at Waterville, in the county of Kennebec and State 5 of Maine, have invented certain new and useful Improvements in Mop-Wrangling Machines; and I do hereby declare that the following is a full, clear, and exact description of the same, reference being had to the annexed drawings, making a part of this specification, and to the letters and figures of reference marked thereon.

The present invention has reference to that class of mop wringing machines comprising a 15 suitable box in which the mop is placed and a presser-board operated by a lever mechanism by which means the mop by compression is relieved of the moisture therein, and the object of the invention is to materially simplify 20 the construction of this class of machines whereby increased effectiveness is obtained and a greater pressure brought upon the mop through a simple arrangement of lever mechanism connecting with the presser-board.

The invention consists in a mop wringing machine constructed substantially as shown in the drawings and hereinafter described and claimed.

30 Figure 1 of the drawings is a perspective view of a mop wringing machine constructed in accordance with my invention. Fig. 2 a transverse sectional elevation. Fig. 3 a detail view in perspective of a portion of the 35 presser board and the end of the lever which connects therewith.

In the accompanying drawings the box in which the mop is placed to relieve the same of moisture, consists of the two sides A, B 40 and the stationary side C, the movable presser-board D forming one side of the box. The sides A and B are preferably perforated for the escape of the moisture from the mop and are detachably connected with each 45 other so that the sides may be separated when desired for packing and transporting or for other purposes. The sides A B have supporting legs a extending therefrom which are connected near their lower ends by a 50 cross-piece or brace b to which is connected a bearing arm c. The cross-brace b is detachably connected to the legs a, the ends of the brace entering slots in the legs and held in position by a suitable key d, and the bearing 55 arm c is held to the cross brace by a key f or by any other suitable means whereby the

cross brace and bearing may be separated from each other when desired. The bottom E of the box is also removable, the same having tongues g projecting from its ends and 60 entering elongated slots in the sides of the box so that the sides may be readily separated. The side C of the box is held between brackets h, two of which project from each of the sides A B, the side C slipping down between them and readily removed therefrom 65 when desired.

The presser-board D is connected to a depending arm F which is pivoted at its lower end to the bearing arm c and extends up 70 through a slot i in the bottom E to allow it to move back and forth in the process of wringing the mop. The presser-board D has bearing brackets j and to these brackets are pivoted one end of link-levers G, the ends of 75 the levers having inwardly projecting pivot-pins k which engage holes l in the brackets, as shown in Fig. 3 of the drawings. The opposite ends of the link-levers G are pivotally connected to cranks q of a crank-bar H, said 80 crank-bar in turn being pivotally connected to curved arms I which project up from the sides A B of the box.

An operating hand-lever J connects with the crank-bar and with one of the link-levers 85 in the following manner; the pin m of the crank-bar H is of sufficient length to extend some distance beyond the curved arm I so that the hand-lever J can be attached thereto by means of the key n so that by turning the 90 hand-lever the crank-bar will be operated. The pin o of one of the cranks q is of sufficient length to connect the end of the lever J thereto by means of a staple or clip p so that by the operation of the lever through its connections as above described, an increased leverage upon the presser-board is obtained. A suitable stop r projecting from one of the 95 sides of the box may be provided to limit the action of the operating hand lever and hooks 100 s project from the back of the machine to engage a tub or vessel containing the water. The sides A and B and the back or side C are held together by the cross brace b and the crank bar H, and by the bottom E with its 105 tongues engaged in the slots in the sides A and B, and the keys in the same outside of the sides.

Having now fully described my invention, what I claim as new and desire to secure by 110 Letters Patent, is:—

A mop wringer comprising a back, sides

with depending legs, and upwardly extended curved arms, a bottom, a presser board, a brace connecting said legs, a bearing arm on said brace, an arm pivoted to said bearing arm and connected with the presser board a crank bar having crank arms mounted in the upper ends of said curved arms, links disposed above the top of said back and pivotally connected to the presser board, arms depending from said crank bar and pivotally connected to said links, an operating lever pivotally mounted on one of said curved arms

above the top of the back and connected to the extended end of one of the pivots joining the link levers and depending arms of the 15 crank bar, and a stop projecting upwardly from one of the sides in the path of said operating lever.

In testimony whereof I affix my signature in presence of two witnesses.

MILO A. ELLIOTT.
